CLAIM

The ornamental design for a rifle, as shown and described.

DESCRIPTION

FIG. 1 is a left side elevation view of a rifle embodying the design of the present invention;

FIG. 2 is a right side elevation view of the rifle of FIG. 1 showing the sole different design feature of the second embodiment of the rifle;

FIG. 3 is a top elevation view of the rifle of FIG. 1; FIG. 4 is a bottom elevation view of the rifle of FIGS. 1 and 7;

FIG. 5 is a front elevation view of the rifle of FIG. 1;

FIG. 6 is a rear elevation view of the rifle of FIG. 1;

FIG. 7 is a partial left side elevation view of a second embodiment of the rifle of FIG. 1; and,

FIG. 8 is a perspective view showing the bipod of the rifle of FIG. 1 in an extended position from the left side wherein the view from the right side showing the bipod of the rifle is identical.

FIG. 6

UNITED STATES PATENT AND TRADEMARK OFFICE
CERTIFICATE OF CORRECTION

PATENT NO. : Des. 403,043
DATED : December 22, 1998
INVENTOR(S) : FRIEDRICH SPEKNER

It is certified that error appears in the above-identified patent and that said Letters Patent is hereby corrected as shown below:

In the FIG. 2 description, after "FIG. 1", "showing the sole different design feature of the second embodiment of the rifle" should be deleted.

In the FIG. 4 description, "FIGS. 1 and 7" should be deleted and --FIG. 1-- should be inserted.

In the FIG. 7 description, after "FIG. 1" insert --showing the sole different design feature of the second embodiment of the rifle--.

In the FIG. 8 description, delete "FIG. 1" and insert --FIGS. 1 and 7--.

Signed and Sealed this

Fourteenth Day of September, 1999

Attest:

Q. TODD DICKINSON
